UNITED STATES PATENT OFFICE.

CHARLES H. VICKERY, OF ATTICA, NEW YORK.

AUTO HEADLIGHT.

Application filed May 24, 1923. Serial No. 641,219.

To all whom it may concern:

Be it known that I, CHARLES H. VICKERY, a citizen of the United States, residing at Attica, in the county of Wyoming and State of New York, have invented a new and useful Auto Headlight, of which the following is a specification.

This invention relates to motor vehicle headlights, the primary object of the invention being to provide a headlight including a plurality of bulbs, novel means being provided for supporting the bulbs whereby the bulbs may be moved into proper relation with respect to the reflector of the lamp, so that if a lamp becomes broken a perfect lamp may brought into operation at the will of the operator.

Another object of the invention is to provide a novel form of switch mechanism whereby only the lamp that is moved to its illuminating position is in circuit with the source of electric supply.

With the foregoing and other objects in view which will appear as the description proceeds, the invention resides in the combination and arrangement of parts and in the details of construction hereinafter described and claimed, it being understood that changes in the precise embodiment of the invention herein disclosed, may be made within the scope of what is claimed, without departing from the spirit of the invention.

Referring to the drawings:

Figure 1 is a fragmental sectional view through the lower portion of a lamp constructed in accordance with the present invention.

Figure 2 is a transverse sectional view through a lamp housing.

Figure 3 is a sectional view taken on line 3-3 of Figure 1.

Figure 4 is a sectional view taken on line 4-4 of Figure 1.

Figure 5 is an elevational view of the lamp supporting disk.

Figure 6 is a sectional view taken on line 6-6 of Figure 4.

Figure 7 is a diagrammatical view of the wiring system.

Referring to the drawings in detail, the reference character 5 designates a lamp housing which is provided with the usual reflector 6, which lamp housing is formed with an opening 7 in its rear wall registering with the opening 8 of the reflector 6 to

accommodate the shaft 9. This shaft 9 forms a part of the rotor shaft of the motor 10 and extends to a position within the reflector 6 as clearly shown by Figure 1 of 60 the drawings.

On the outer ends of the shaft 9 is positioned a disk 11 formed of suitable insulating material to which disk is secured the supporting disk 12 which is formed of a 65 conductive material, the disks 11 and 12 being secured together by means of the rivets 13.

Mounted on the disk 12 are the lamp sockets 14, which lamp sockets may be of 70 any desired number and arranged in any desired manner on the disk 12, the lamp sockets being however preferably formed with slots 15 to accommodate the pins 16 provided on the lamps, so that the lamps 75 may be readily positioned.

In each lamp socket is an insulating disk 17 that supports a contact point 18 which has connection with the wire 19 that is connected with the contact member 20 associated therewith. These contact members 20 are secured to the disk 11, it being understood that there is provided a contact member 20 and wire 19 for each lamp supported by the disks so that when a contact 85 member is in its active position, the lamp associated therewith will be in circuit with the battery supplying the electric energy for lighting the lamp.

An arm indicated at 21 has connection 90 with the inner surface of the lamp housing 5 and insulated therefrom by means of the insulating member 22, the arm being in circuit with a source of electric supply through the wire 23 supported within the 95 insulating tube 24. Carried at the outer end of the arm 21 is a spring finger 24' adapted to contact with the insulating member 20 as it is moved into proximity with the finger.

The motor 10 is of a particular construction and embodies pairs of magnetic coils 25, which coils are disposed adjacent to the ends of the arm 26 mounted on the inner end of the shaft 9 so that when the magnetic coils are energized, the arm 26 will be rotated by means of the magnetic influences of the coils attracting the arm 26.

The magnetic coils 25 are in independent circuits and are controlled by means of 110 the switch member 27 mounted on the instrument board of the vehicle where the

same may be conveniently operated by the driver of the vehicle.

In the use of the device, it is contemplated to support an exceptionally bright lamp, a medium lamp and a lamp partially frosted, so that by energizing certain magnetic coils 25, predetermined lamps may be brought to their proper illuminating positions.

10 Assuming that the operator desires to move an exceptionally bright light into its illuminating position, and moves the lamp which is in an illuminating position to its inactive position, the switch member 27 is 15 operated and moved to a predetermined point to energize certain coils 25 whereupon the shaft 9 is rotated moving the disks supported at the outer ends thereof and consequently moving the desired lamp to its 20 proper position.

It is obvious that when the lamp is in focus, the circuit to the lamp is completed through the finger 27, contact member 20, and grounded through the metallic disk 12 25 and shaft 9 of the motor.

The switch 28 controls the circuit to the lamp and it is to be understood that when the motor has been operated to move the desired lamp to its illuminating position, the

circuit to the motor may be broken by moving the switch 27, and the circuit to the lamps completed through the switch 28.

What is claimed as new is:—

In combination with a lamp housing, a motor supported at the rear of the housing, a shaft extending from the motor and having its forward end disposed within the lamp housing, a disk of insulating material supported on the forward end of the shaft, a lamp supporting disk secured to the insulated disk, said insulating disk carrying spaced contact members in circuit with the lamps supported on the disks, a spring finger adapted to contact with the contact members to complete the circuit to the lamps, means for supplying electric energy to the motor to operate the shaft and move the lamps into displaying positions, and means for controlling the circuits to the lamps.

In testimony that I claim the foregoing as my own, I have hereto affixed my signature in the presence of two witnesses.

CHARLES H. VICKERY.

Witnesses:

WILLIAM HALL,
C. L. MARTIN.
